UNITED STATES PATENT OFFICE.

XENOPHON CAVERNO, OF KEWANEE, ILLINOIS.

SEPTIC TANK.

1,148,500.

Specification of Letters Patent. Patented Aug. 3, 1915.

Application filed April 27, 1914. Serial No. 834,615.

To all whom it may concern:

Be it known that I, XENOPHON CAVERNO, a citizen of the United States, residing at Kewanee, county of Henry, and State of Illinois, have invented new and useful Improvements in Septic Tanks, of which the following is a specification.

My invention relates to improvements in septic tanks with especial reference to the 10 structure and coöperative arrangement of the inlet and outlet members.

The object of my invention is to provide inlet and outlet members which are adapted to be constructed in a shop or factory, shipped 15 to the point of use, and set up in a mold as a single unit or set of units having a fixed relation to each other, and a necessary relation to the walls of the tank, whereby inexperienced persons may construct tank 20 walls or molds for tank walls and fill them with concrete without danger of errors, such as would interfere with or prevent the proper operation of the tanks.

It is well known that an efficient septic 25 tank requires an inlet adapted for delivery of sewage to the tank with a minimum of agitation and under conditions which provide for a maximum distance of travel in the tank before reaching the outlet, and 30 that both the inlet and the outlet should be located below the surface of the liquid and above the bottom of the tank to avoid interference with the accumulated sludge on the bottom, or with the scum at the top. The 35 usual practice has therefore been to provide an inlet at one end of an elongated tank and an outlet at the other end, each being located at an intermediate point, between the bottom and the top of the tank. My im- 40 proved construction, however, contemplates the location of both the inlet and the outlet in what would be called the rear end portion of the tank.

It is also my object to provide means for 45 securing an intermittent delivery of the effluent by providing an outlet chamber into which the effluent passes from the tank proper and from which it is discharged to the exterior filter beds.

In the drawings—Figure 1 is a longitudinal 50 sectional view of a septic tank embodying my invention, drawn to a plane cutting the siphon and outlet ducts axially. Fig. 2 is a transverse sectional view, drawn on line $x-x$ of Fig. 1. Fig. 3 is a plan view 55 with the cap or top wall partially broken

away. Fig. 4 is a side elevation of a mold showing the outer wall of the mold, *i. e.* the earth adjacent to the excavation, in section, and showing the metallic members or units 60 as they are assembled with reference to the inner wall of the mold preparatory to the insertion of the concrete filling which is to form the wall of the completed tank.

Like parts are identified by the same reference letters throughout the several views.

The tank is preferably formed of concrete, with bottom A, front end wall B, side wall C and cap D, all formed integrally or as nearly so as possible. The lower portion E of the rear wall may be also formed of concrete and the upper portion comprises 70 a metallic member having the form of a rectangular box with front and rear walls e, e', and with its end walls embedded in the 75 side walls C, C, of the tank. The wall e of this metallic member is provided with a longitudinal slot F near its lower margin, and the wall e' is provided with a similar slot F' near its upper margin, said member thus 80 providing a passage, the inlet to which is the slot F and which leads upwardly between the walls e, e' to the outlet or over-flow slot F'.

The portion E of the rear wall of the tank 85 is thickened and extended rearwardly from its upper margin to form a floor G for an outlet chamber, the walls C being extended to form the sides of this outlet chamber and the cap D being similarly extended to form 90 the top. The rear wall G' completes the inclosure, forming an outlet cavity g within which a siphon bell H is located in a position covering the upwardly projecting end 95 of an outlet duct H', the initial end of which extends down vertically and is formed into a loop at h which constitutes a trap, the other leg of the loop extending upwardly, preferably in a substantially vertical direction and connecting with a horizontal pipe h' which forms a continuation 100 of the duct and provides for a discharge of the effluent rearwardly from the structure. A branch pipe h'' extends from the pipe h' upwardly into the over-flow cavity g to a 105 point near the top of the cavity, and constitutes a vent and overflow.

The initial leg H' of the trap is connected with the rear wall e' of the over-flow member by a clamping bracket I, secured to said 110 rear wall and clamped around the pipe section or trap leg H', whereby the outlet duct

is rigidly connected with the over-flow member. A similar clamping bracket J connects the wall *e* of the over-flow member with an elbowed inlet duct K, leading downwardly 5 into the receiving or disposal cavity L of the tank from the sewer main or duct M. The elbowed member K is provided with a horizontal leg K' through which the sewage is delivered in the direction indicated by the 10 arrow in Fig. 1, viz: in the direction of the front wall B.

With the above described construction, it is obvious that all members pertaining to the 15 inlet and outlet parts of the tank are integrally connected together in a fixed relation to the over-flow member, which member constitutes the upper portion of the rear wall of the receiving cavity in which the sewage is disintegrated. And since this 20 over-flow member is necessarily placed in a fixed relation to the mold preparatory to filling in the concrete, and in fact forms part of the inner wall of the mold, it is obvious that all the elements rigidly connected 25 therewith, will necessarily be held in proper position for successful and efficient operation, if so assembled and secured to the over-flow member at the shop or factory where these parts are constructed. The upper 30 margin of the bracket I determines the level of the floor G of the over-flow cavity. The length of the over-flow member determines the width of the tank and to a large extent also determines its depth, since it will be 35 understood that the slot F must be located somewhere near the middle of the space between the top of the liquid in the tank or the top of the tank and the bottom. The outlet 40 passage being vertical between walls *e* and *e'* and the delivery being upward in this passage, moss or other solid matter will not collect therein. The upper level of the liquid in the tank is determined by the position 45 of the slot F'. The direction of delivery of the inflow is determined by the member K' of the inlet pipe, as is also the depth below the surface of the liquid at which the inflow is to be delivered. It is therefore impossible 50 to install the metallic inlet and outlet unit above described in any other manner than that in which it is illustrated in the drawings and this insures a delivery of sewage in the direction of the front end B of the tank without material agitation, the influx 55 being slowly distributed and the solid portions settling to the bottom. As these gradually accumulate, a substance resembling moss forms on its surface. This moss is filled with gas bubbles and the buoyant effect of these gas bubbles tears pieces of the 60 "moss" loose and it rises through the liquid. As it rises, the gas bubbles escape and the moss again settles toward the bottom. This process of rising and falling continues 65 as the moss is gradually reduced to liquids

and gases, the change being due to the action of anaerobic bacteria. Before reaching the outlet, disintegration will have been completed to such an extent that the central portion of the liquid will be substantially 70 clear. When there is a fresh delivery of sewage through the inlet, the clear or substantially clear liquid at the outlet will be displaced and slowly driven up through the outlet passage between the walls *e*, *e'*. The 75 liquid near the bridge wall is always free or substantially free from "moss", particularly in the portion between the bottom of the tank where sludge may be found and the top of the liquid in the tank, which will 80 be normally covered by a scum. This clarified central body of liquid near the middle portion of the bridge wall entered the tank through previous deliveries and perhaps at periods several hours or even days in advance of the delivery which causes the discharge of any given portion through the outlet, but when a discharge of this clarified liquid or effluent occurs, it passes upwardly 85 in the outlet member to the over-flow slot 90 F' and drops into the over-flow chamber g, where it accumulates until a sufficient depth is attained to start the siphon. The liquid will then discharge until the air is admitted 95 to the siphon bell through the duct N. In 100 this manner an intermittent discharge is permitted, thus greatly increasing the efficiency of the filter bed over that which is secured where a small constant discharge is permitted. By using the siphon, the filter 105 bed is thoroughly charged with water during the discharge interval, after which the flow ceases and as the water percolates away through the soil of the filter bed, air is drawn in and the filter bed thoroughly aerated, preparatory to the next discharge.

It will be observed that the inlet duct K is provided with an aperture O in the upper wall of the upper elbow which permits the escape of gas and air from the inlet duct 110 which would otherwise be driven into the liquid of the tank. This would not only increase the agitation of the liquid, but would aerate it and interfere with the development of anaerobic bacteria in sufficient numbers to disintegrate the sewage. The air and gas passing through the opening O, together with any other gas or air in the tank, is permitted to pass through an opening P in the wall *e* into the outlet chamber 120 g, from which chamber it is drawn out through the vent pipe h" during the operation of the siphon. This prevents a development of pressure in the liquefying tank due to the in-rush of air with the sewage, 125 which would otherwise force the gases in the top of the liquefying tank through the cracks around the man-hole cover. The openings O and P also permit air to enter the tank and siphon chamber during the dis- 130

- charge of the siphon to take the place of the discharging liquid. If air were not thus admitted, the discharge of the liquid from the siphon chamber would tend to produce a 5 partial vacuum in such chamber. This would not only interfere with the out-flow of the liquid, but it would also draw water over the bridge wall and lower the level of the sewage in the liquefying tank until the 10 atmospheric pressure in the two chambers equalizes. Such variations in the level of the sewage in the liquefying chamber or tank would be detrimental to the disintegrating process above described.
- 15 I claim—
1. As a new article of manufacture, a back wall member for septic tanks, having a passage therethrough and provided with an inlet duct secured to one face thereof 20 and an outlet duct secured to one face thereof, all in fixed and operative relation each to the other, and adapted for shipment as a septic tank unit designed for assembly with the other portions of a septic tank at the 25 place of use, substantially as described.
  2. A metallic back wall member for septic tanks, comprising a hollow member having its inner side slotted near the lower margin, and its outer side slotted near its upper 30 margin, and having a tank inlet duct secured thereto, and adapted to direct the inflow toward the opposite tank wall.
  3. The combination with a hollow metallic back wall member for septic tanks, 35 provided with an overflow passage, of an inlet duct secured in fixed relation to said back wall member by metallic connections, and an outlet duct secured in fixed relation to said back wall member by metallic connections.
  4. A septic tank, including the combination with tank walls provided with an outlet, of an inlet duct extending through a side wall of the tank at a point above the 45 level of the outlet and provided with a down turned elbowed member, said duct having its upper wall apertured within the tank and above the level of the outlet to provide a vent for air and gas; said duct being also 50 provided with an elbowed delivery portion below the outlet adapted for a horizontal discharge of liquid below the normal level of the liquid in the tank, whereby air and gas may be discharged into the tank above 55 the level of the liquid therein, and liquid may be delivered below such level with minimum disturbance to the contents of the tank.
  5. An inlet duct for septic tanks comprising a member adapted to extend through a side wall of the tank and provided with a down turned elbowed member having its upper wall apertured, said duct being also provided with a lower elbow and a delivery 60 portion extending substantially at right angles to both of the other members, in combination with an overflow member secured to the down-turned portion on the opposite side from that in which the inlet extends and in fixed relation to the inlet duct independently of the tank walls. 70
  6. A metallic unit for septic tanks, comprising an inlet member, an overflow member and an outlet member, secured together independently of the other portions of the tank, and held in fixed relation to each other by the securing means, whereby said unit may be assembled in one place and shipped to another place for assembly with the other members of a septic tank. 75
  7. A metallic unit for septic tanks, comprising an inlet member, an overflow member and an outlet member, secured together independently of the other portions of the tank, and held in fixed relation to each other by the securing means, whereby said unit may be assembled in one place and shipped to another place for assembly with the other members of a septic tank, said inlet member and overflow member being adapted to deliver fluid in opposite directions and said inlet member being adapted for delivery at a lower level than the outlet member. 80
  8. A septic tank comprising the combination with side and bottom walls, of an end wall comprising a concrete lower portion surmounted by a hollow metallic member having its ends embedded in the side walls, the inner face of said metallic member being slotted near its lower margin along a line substantially midway between the top and bottom of the liquid containing portion of the tank and having its outer face provided with an outlet slot near its upper margin; said slots, together with the hollow interior of the metallic member forming an upwardly extending outlet passage having a horizontal inlet at its lower end adapted to receive liquid from the middle portion of the tank with minimum disturbance to the top and bottom portions thereof. 95
  9. A septic tank comprising the combination with side and bottom walls, of an end wall having a concrete lower portion surmounted by a hollow metallic member having its ends embedded in the side walls, and having its inner face slotted near the lower margin and its outer face slotted near its upper margin and forming, with the hollow interior, an upwardly extending overflow passage, said concrete portion of the back wall being extended rearwardly from its upper margin and provided with raised side and end walls, constituting an auxiliary chamber to receive the effluent from said 110 overflow passage, said auxiliary chamber being provided with an outlet. 115
  10. A septic tank comprising the combination with side and bottom walls, of an end wall having a concrete lower portion sur- 120
  - 65 125
  - 130

mounted by a hollow metallic member having its end embedded in the side walls, and having its inner face slotted near the lower margin and its outer face slotted near its 5 upper margin and forming, with the hollow interior, an upwardly extending overflow passage, said concrete portion of the back wall being extended rearwardly from its upper margin and provided with raised side 10 and end walls, constituting an auxiliary chamber to receive the effluent from said overflow passage, said auxiliary chamber being provided with a metallic outlet duct including a siphon and a trap and permanently connected in fixed relation to the 15 hollow metallic back wall member.

11. A septic tank having a receiving chamber and an effluent chamber of less depth, each of said chambers being provided 20 with concrete walls, in combination with a metallic hollow overflow partition between said chambers, an inlet duct in the receiving chamber clamped to said partition, an outlet duct in the effluent chamber clamped to said 25 partition, a siphon bell covering the receiving end of the outlet duct, and the remaining portions of said duct being embedded in the concrete walls of said chamber and including a trap and a vent duct projecting 30 from the outlet duct beyond the trap upwardly into the effluent chamber.

12. A septic tank having a receiving chamber and an effluent chamber of less depth, each of said chambers being provided 35 with concrete walls, in combination with a metallic hollow overflow partition between said chambers, an inlet duct in the receiving chamber clamped to said partition, an outlet duct in the effluent chamber clamped to said partition, a siphon 40

bell covering the receiving end of the outlet duct, and the remaining portions of said duct being embedded in the concrete walls of said chamber and including a trap and a vent duct projecting from the outlet 45 duct beyond the trap upwardly into the effluent chamber, said inlet duct and overflow partition having apertures in their upper portions through which air and gas may pass to the vent duct. 50

13. A septic tank, having concrete side walls and an outlet member, having marginal ribs at its respective ends embedded in said side walls and provided with inner and outer wall plates spaced apart, the inner 55 plate having a slot along its lower margin and the outer plate having a slot near its upper margin, said slots extending transversely of the tank and communicating with the space between the plates to provide an 60 outlet passage leading from the middle portion of the end wall, upwardly to the slot in the outer plate.

14. An outlet member for septic tanks provided with an outlet passage extending 65 upwardly therethrough, said outlet member being provided near its respective ends with means for connecting the walls of a mold to the front and rear faces thereof, the ends of said member being adapted to form projecting portions of the mold wall adapted to be permanently embedded in a plastic filling for such mold. 70

In testimony whereof I affix my signature in the presence of two witnesses.

XENOPHON CAVERNO.
